CLAIM

The ornamental design for a privacy fence, as shown and described.

DESCRIPTION

FIG. 1 is a front, top perspective view of a privacy fence, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines show portions of the privacy fence that form no part of the claimed design.

The dashed lines in the figures illustrate portions of the privacy fence that form no part of the claimed design.
